(57) **CLAIM**

The ornamental design for a display screen with graphical user interface for a sphygmomanometer with wireless communication device, as shown and described.

DESCRIPTION

The file of this patent contains a least one drawing/photograph executed in color. Copies of this patent with color drawings/photographs will be provided by the united states Patent and Trademark office upon request and payment of the necessary fee.

FIG. 1 is a front view of a first embodiment of a display screen with graphical user interface for a sphygmomanometer with wireless communication device showing the first image of our new design;

FIG. 2 is a front view showing a second image thereof;

FIG. 3 is a front view showing a third image thereof;

FIG. 4 is a front view showing a fourth image thereof;

FIG. 5 is a front view showing a fifth image thereof; and

FIG. 6 is a front view showing a sixth image thereof.

FIG. 7 is a front view of a second embodiment of a display screen with graphical user interface for a sphygmomanometer with wireless communication device showing the first image of our new design;

FIG. 8 is a front view showing a second image thereof;

FIG. 9 is a front view showing a third image thereof;

FIG. 10 is a front view showing a fourth image thereof;

FIG. 11 is a front view showing a fifth image thereof; and,

FIG. 12 is a front view showing a sixth image thereof.

The appearance of the graphical user interface sequentially transitions between the images shown in FIGS. 1-6 and FIGS. 7-12. The process or period in which one image transitions into another image forms no part of the claimed design.

(Continued)

The dashed broken lines showing a sphygmomanometer with wireless communication device illustrate environmental structure that forms no part of the claimed design.
